UNITED STATES PATENT OFFICE.

ISAAC BAUER, OF HARTFORD, CONNECTICUT, ASSIGNOR TO THE NEW ENGLAND ENAMELING COMPANY, OF MIDDLETOWN, CONNECTICUT, A CORPORATION.

TEAPOT.

1,123,467.

Specification of Letters Patent.

Patented Jan. 5, 1915.

Application filed April 3, 1913. Serial No. 758,702.

To all whom it may concern:

Be it known that I, ISAAC BAUER, a citizen of the United States, residing at Hartford, in the county of Hartford and State 5 of Connecticut, have invented certain new and useful Improvements in Teapots, of which the following is a specification.

My invention relates to improvements in tea pots and the object of my improvement 10 is to provide a tea pot with a tea ball and supporting means therefor that are simple and reliable in use.

In the accompanying drawing:—Figure 1 is a central vertical section of my improved tea pot. Fig. 2 is a similar view on an enlarged scale of the upper part of the same, and with the tea ball in elevated position. Fig. 3 is a similar view of the same with the lever in an intermediate position. 20 Fig. 4 is a fragmentary view corresponding to Fig. 2 of a modification of the cover. Fig. 5 is a similar view of the same, with the parts in the intermediate position shown in Fig. 3. Fig. 6 is a similar view of the top 25 of the stem and the end piece engaged therewith.

My tea pot comprises a body 10 having a circular opening 11 at the top, and a cover 12. The cover 12 has a dome-shaped top 30 portion 13, a cylindrical bottom portion 14 fitting the opening 11, and a flange 15 at the junction of the said top portion 13 and bottom portion 14 which overhangs the body portion 10. The dome-shaped top portion 13 is provided at the apex with an upwardly directed tubular stem 16 on which is mounted a knob 17, which latter may be of wood. The stem 16 may be of appreciable thickness, in which case the upper end 21 is 35 finished off conical so as to provide a sharp bearing edge 18 at the extreme upper end and which corresponds to the upper end of the axial bore 19. The upper wall 20 of the knob 17 is preferably finished off conical 40 and approximately in continuation of the conical upper end of the stem 16.

The tea ball 31 is as usual made of two parts of foraminous material and the upper part is shaped to conform to and to fit 50 within the interior of the dome shaped portion 13 of the cover. A chain 22 is connected by the lower end to the upper end of the tea ball 31 and is of sufficient length to extend through the stem 16 and have the 55 upper end 23 project above the same. The

said upper end 23 is connected to the inner end 26 of a lever 25.

At the outer end 27 of the lever 25 there is connected one end of a chain 28 and to the other end of which is attached an end piece 60 29 that serves as a combined finger piece and counterweight.

When the tea ball 31 is dropped within the body portion 10 the end piece 29 rests on the knob 17 and supports the same 65 through the medium of the chain 28, lever 25, and chain 22.

When it is desired to bring the tea ball 31 to the elevated position within the dome-shaped portion 13 the end piece 29 is grasped 70 and the tea ball is lifted to the position desired. Then a side-wise movement is given to the end piece 29 and the hold on the same is released, so that the same is brought to the pendent position as shown in Fig. 2. In 75 this position and in the intermediate position shown in Fig. 3 the portion of the lever 25 adjacent the pivotally connected end 26 is brought into engagement with the conical bearing edge 18 of the stem 16, which serves 80 as a fulcrum therefor. The end piece 29, which has appreciable weight, serves as the power to over-balance the load consisting of the tea ball 31 and to maintain the same in the elevated position. 85

In the modification shown in Fig. 4 the stem 16^a consists of a thin tube, the upper end 18^a of which projects slightly above the knob 17^a.

The end piece 29 as stated is of appreciable weight and comprises a body portion 30 of metal and may be provided with a finger piece proper 31 of wood and which may be secured thereto in any convenient manner. The exposed end 33 of the body portion 30 90 is provided with an axially extending lug 32 to which the chain 28 is attached. The lug 32 is a fit for the end of the stem 16 or 16^a. I prefer to have the portion of the wall of the said exposed end 33 surrounding the lug 100 32 which is the bottom wall shown in Fig. 6, recessed as shown at 34 so that the outer edge 35 will engage with the upper end of the knob 17 or 17^a and serve as a support 105 thereto and will house in the recess 34 the upper bearing edge 18 or 18^a of the stem 16 or 16^a.

The body portion of the pot may be made 110 of enameled ware or aluminum or other

suitable material and the cover and the tea ball are preferably made of aluminum.

The fact that the bearing edge that serves as a fulcrum for the lever is close to the point of pivotal connection of the tea ball permits of over-balancing the weight of the tea ball with a relatively short lever and small weight.

As shown, the lever 25 is made in the form of a flat bar. When the same is connected to the tea ball by means of the flexible connection, such as is provided by the chain 22, the said lever may engage with the fulcrum either edgewise, as shown in the drawing, or flatwise, according to the position it is in when released; and in either position will operate to support the tea ball, even with a small counter-weight 29 as in both cases, owing to the fact that the fulcrum is appreciably elevated relatively to the adjacent parts; an extremely short lever arm is provided on the side of the tea ball.

I claim as my invention:—

In combination in a tea pot, a tea ball, a pot body, a cover therefor, a knob on said

cover having a bore, a lining for the said bore, extending slightly above the upper end of the said bore, the said lining being formed suitably to provide a narrow bearing edge that is positively positioned above the upper end of the said knob, a supporting device for the said tea ball, connected thereto by one end, and passing through the said lining, a combined counterweight and finger piece connected to the other end of the said supporting device, and the said supporting device comprising a length of chain at each of the said ends and a lever interposed between the said lengths of chain, whereby lifting the said finger piece will serve to elevate the said lever and tea ball and swinging the said finger piece to one side relatively to the said knob after being so lifted and releasing the same will permit the said lever to engage with the said bearing edge.

ISAAC BAUER.
